(57) **CLAIM**

The ornamental design for an electric motorcycle, as shown and described.

DESCRIPTION

FIG. 1 is a perspective view of an electric motorcycle showing our new design;

FIG. 2 is a front view thereof;

FIG. 3 is a back view thereof;

FIG. 4 is an enlarged left view thereof;

FIG. 5 is an enlarged right view thereof;

FIG. 6 is a top view thereof;

FIG. 7 is a bottom view thereof;

FIG. 8 is an enlarged view of the encircled area 8 of FIG. 1; and,

FIG. 9 is an enlarged view of the encircled area 9 of FIG. 1. The broken lines shown on the drawings depict portions of the electric motorcycle that form no part of the claimed design. The dot-dash lines depict the enlarged view boundaries that do not form part of the claimed design.

1 Claim, 9 Drawing Sheets
